[57] ABSTRACT

Ship or building rows of windows are cleaned by a series of motor-driven, essentially vertical, rotation symmetrical, preferably cylindrical brushes mounted in a frame having a portion thereof dependent from a rail secured to the front of the building or side of the ship over the windows to be cleaned.

MOTOR-DRIVEN WASHING APPARATUS

CROSS-REFERENCE TO RELATED APPLICATION

The present application is a continuation-in-part of my copending application Ser. No. 270,987, filed July 12, 1972, and now abandoned, entitled "Motor-Driven Washing Apparatus," the contents of which are hereby incorporated by reference.

FIELD OF THE INVENTION

The present invention relates to a motor-driven washing apparatus especially intended for washing rows of windows on ships and buildings.

Prior to the invention building window washing was done manually, which is both expensive, and, as to ships at sea, sometimes impossible. Even in a moderately rough sea the lower rows of windows on a passenger vessel quickly become opaque or obscured due to salt precipitates from spraywater. It is therefore desirable to provide simple and efficient means to keep the windows clean without resorting to manual washing.

In public buildings, restaurants, hotels and the like located at the sea-side similar requirements prevail. It should therefore be understood that although the invention is described as it relates to ships, this does not limit the invention which may be applied to the washing of windows and fronts of buildings as well.

According to the invention the above problem is solved by the provision of a motor-driven washing apparatus constructed and operated as hereinafter described.

Further details and features of an apparatus according to the invention will be evident from the following specification and drawings, and the appended claims.

DESCRIPTION OF THE DRAWINGS

FIG. 1 shows the apparatus in side view, perpendicular to the side of the ship;

FIG. 2 is a side view, partly in section, of the apparatus viewed parallel to the side of the ship;

FIG. 3 is a plan view of the apparatus;

FIG. 4 shows a detail of the apparatus of FIG. 2, namely the lower support arm, viewed from below;

FIG. 5 shows another detail of the apparatus of FIG. 2, namely the hollow arm and two conduits conducted through this hollow arm; and

FIG. 6 shows schematically the position of the conduits when the washing unit moves along the track from one extreme position to another.

The washing apparatus according to the invention comprises a transport motor 1 which provides the necessary force to move the washing apparatus, and a second motor 2 for rotating a cylindrical, vertical brush 3. Motors 1 and 2 are secured to the upper part of a square or oblong framework 4. At the midpoint of the lower side of the framework there is a bearing for the vertical brush 3.

A support rail 5 is secured to the side of the ship (not shown) above the rows of windows. The frontal, lower edge of the support rail 5 carries a rack 6, the gears of which face inwards. The motor 1 drives a gear wheel 8 via a suitable gear box or similar transmission 7, which gear wheel 8 meshes with the rack 6. An idling counter pressure roller 9 acting from the opposite side provides the connection between rack and gear wheel. In the frame 4, some distance from the wheel 8 there is similar, but idling gear wheel 10 which together with the

idler roller 11 prevents the apparatus from turning in the vertical direction with respect to the support rail 5. At the lower edge of the framework 4 is supported to the side of the ship (not shown) by means of an arm 12 carrying at its free end a roller 13. The arm 12 is secured to the frame at the point where the lower shaft of the brush 3 is journalled. One or both of the vertical edge members of the frame 4, which as well as the rest of the framework are manufactured from metal tube material, are provided or shaped with water nozzles, such as the nozzles 14 directed perpendicularly towards the side of the ship and the windows (not shown) for rinsing, and the nozzles 15, which are directed inclined with respect to the side of the ship and/or the windows so that the water jets reach the rotating brush 3.

Under the support rail 5 there are two U-shaped channels 16a and 16b, serving as ducts for two cables 17a and 17b, respectively, for water and electricity, respectively. A transverse hollow arm 18 connected to the apparatus by a support member 19, is situated under the support rail 5 and extends at one end out over said channels 16a and 16b. The cables 17a and 17b are drawn out of the channels 16a and 16b and are laid in bows in the hollow arm 18. As shown in FIGS. 2 and 3, the cables 17a and 17b in channels 16a and 16b enter the hollow arm 18 at one end thereof via openings 18a and 18b, respectively, then pass through the hollow arm 18 to the other end thereof, and then exit the hollow arm 18 via opening 18c. The cables 17a and 17b pass from exit 18c downwardly along support member 19 and through holding device 17c (FIG. 2). The cable 17a then extends along the washing apparatus to the framework 4 and the end of the cable 17a is connected to a hollow part of the framework 4 by a connection 17d (FIG. 1). The hollow part of the framework 4 is provided with the nozzles 14 and 15 (FIG. 3), and thus these nozzles will receive water from the cable 17a. The cable 17b extends along the washing apparatus and is connected to an electrical terminal 17d for the two motors 1 and 2 by a plug 17f (FIGS. 2 and 3).

As shown in FIG. 6, the cables 17a and 17b are connected to the ship or the building at the mid-point of the path of travel of the washing unit. The connections are shown schematically at 17g and 17h, corresponding to terminal 17d and plug 17f, respectively. When the washing apparatus is positioned in one extreme position (A), the cables 17a and 17b extend from the connections 17g and 17h to the hollow arm 18 and essentially lay straight on the bottom side of the channels 16a and 16b. When the washing apparatus moves to the right to position (B), the cables 17a and 17b will be laid in a bow in the channels 16a and 16b as shown. When the washing apparatus is positioned in the other extreme position (C), the cables 17a and 17b lay essentially straight on the bottom side of the other part of the channels 16a and 16b, as shown by dotted lines.

While not essential, the hollow arm 18 is preferably journalled in the support member 19 by a member 19a. Thus, the hollow arm will turn about its longitudinal axis when the washing apparatus is moving along its path. The result of a turnable arm 18 is that when the washing unit executes its reciprocation movement, the parts of the cables 17a and 17b laying nearest the hollow arm 18 will always extend in a slight bow so as to protect the cables from bending stresses. The extension of the cables 17a and 17b nearest the arm 18 when the

washing apparatus is positioned in two different positions is shown in FIG. 5.

It should be realized that the embodiment described may be modified in many ways without departing from the scope of the invention. It is for example possible to use the same motor for transport as well as for driving the brush, if a proper gearbox is used which gives the desired travelling speed as well as the desired rotational speed of the brush. It is of course also possible to use more than one brush in one and the same apparatus in parallel, either driving them from a common motor or from individual motors.

Provided that the brush speed and direction of rotation has a fixed relation to the speed of travel and the direction of the apparatus it may be practical to drive the lower support roller 13 from the shaft of the brush especially if the apparatus is so high that for example the brush extends over two or more rows of windows. In the latter case the brush may have a comparatively smaller axial length than the length of the shaft, and be provided with means (not shown) for positioning the brush at any desired axial location so as to, for example, clean one row of windows at a time. The nozzles may then either be axially movable together with the brush or they may be divided into groups, one for each row of windows. The brush is preferably of the kind used in automatic car washing equipment, i.e. provided with long, flexible bristles 20 of NYLON or other suitable synthetic material which is thrown out and makes a soft, resiliant contact with the windows when the brush rotates. Finally the washing apparatus according to the invention may be provided with suitable end-of-travel or other suitable contacts for causing the apparatus to travel to and fro between predetermined limits, as well as with means for moving the brush to different axial positions in order to clean different rows of windows. These and other similar arrangements and means will be clear to those skilled in the art.

What is claimed is:

1. An apparatus for cleaning vertical surfaces of a ship or building comprising
  - a. a rail member disposed horizontally on said surface, said rail member having, in cross-section, a horizontal covering portion extending outwardly

from said surface, a support portion extending downwardly from the outermost edge of said covering portion, and a horizontal track portion extending inwardly towards said surface from the bottommost edge of said support portion,

- b. at least one U-shaped channel disposed horizontally on said surface under said covering portion of said rail member, said channel being operable to receive a conduit, and
- c. a movable washing unit comprising
  - i. a frame;
  - ii. wheel means rotatably mounted on said frame for engagement with upper surface of said track portion of said rail and operable to support said washing unit during movement along said rail;
  - iii. means operable to move said washing unit along said rail;
  - iv. at least one vertical brush means rotatably mounted on said frame for washing engagement with said surface;
  - v. means operable to rotate said brush means;
  - vi. wash fluid spray means; and
  - vii. a hollow arm disposed on said frame so as to ride under said covering portion of said rail upon engagement of said wheel means with said track portion, said arm being operable to receive a conduit at one end from said channel and conduct said conduit through its hollow core to said washing unit.

2. An apparatus as defined in claim 1 wherein said hollow arm is pivotably mounted on said frame.

3. An apparatus as defined in claim 1 wherein the upper surface of said track portion is a rack and said wheel means is at least one pinion engageable therewith.

4. An apparatus as defined in claim 1 wherein said channel is operable to receive a hose conduit and a second U-shaped channel is disposed on said first channel, said second channel being operable to receive an electrical cable.

5. An apparatus according to claim 4 wherein the bottom of said first channel is lower than the bottom of said second channel.
